(57) **CLAIM**

The ornamental design for a bio-modulation light therapy device for blood circulation enhancement comprising graduated scale as shown and described.

DESCRIPTION

The file of this patent contains at least one drawing/photograph executed in color. Copies of this patent with color drawing(s)/photograph(s) will be provided by the Office upon request and payment of the necessary fee.

1. Bio-modulation light therapy device for blood circulation enhancement comprising graduated scale

1.1 : Perspective

1.2 : Front

1.3 : Back

1.4 : Left

1.5 : Right

1.6 : Top

1.7 : Bottom

1.8 : Exploded

The present design is used for irradiating light onto the blood after confirming the treated location using the graduated scale.
